B. GOLDSTEIN ET AL.
MULTIPLE DRINK MIXER.
FILED JULY 18, 1921.

By

Attilton Buck
Attorney

UNITED STATES PATENT OFFICE.

BARNEY GOLDSTEIN AND GEORGE L. McDONAUGH, OF WASHINGTON, DISTRICT OF COLUMBIA; SAID McDONAUGH ASSIGNOR TO SAID GOLDSTEIN.

MULTIPLE-DRINK MIXER.

Application filed July 18, 1921. Serial No. 485,657.

To all whom it may concern:

Be it known that we, BARNEY GOLDSTEIN and GEORGE L. McDONAUGH, citizens of the United States, residing at Washington, in 5 the District of Columbia, have invented certain new and useful Improvements in a Multiple-Drink Mixer, of which the following is a specification.

This invention relates to certain new and 10 useful improvements in a multiple drink mixer and has for its primary object a device of this character in which a number of drinks in different containers may be mixed at one operation and by a single mixing 15 device.

The invention has for another object the provision of a multiple mixer in which a single motor or the like may be employed for operating a plurality of parallel shafts 20 having mixing members mounted thereon, a simple supporting means and driving connections being provided for the shafts to transmit power from the main or motor shaft to the auxiliary shafts.

25 A further object of the invention resides in the provision of a plurality of mixing members spaced from one another and adapted to be operated from a single motor, suitable supporting members being mounted 30 on a motor or the like from which the power is transmitted to the various mixer carrying shafts.

The invention has for still another object the provision of a multiple drink mixer of 35 the character stated in which may be employed the conventional form of motor and mounting for the latter now employed for mixing a single drink.

The invention has for still a further object 40 a multiple drink mixer by the addition of side bearing brackets and auxiliary mixing members with driving connections adapted to be applied to the supporting means for the motor of the conventional 45 form of mixing device now employed for mixing a single drink, so that a number of drinks in separate containers may be mixed with one operation of the motor.

A still further object of the invention re- 50 sides in the provision of an attachment of the character stated for the conventional form of drink mixer which may be readily applied to convert the single drink mixer into a multiple drink mixer at the minimum 55 cost.

With the foregoing and other objects in view which will appear as the description proceeds the invention consists in the novel construction, combination and arrangement of co-operating elements as hereinafter 60 more specifically set forth, claimed and shown in the accompanying drawings forming a part of the present application and in which:

Figure 1 is a side elevation of the conventional form of drink mixer converted into a multiple drink mixer by addition of the attachment forming the subject matter of this invention.

Figure 2 is a front elevation of the multiple drink mixer, as shown in Figure 1.

Referring more in detail to the drawings in which similar reference characters designate corresponding parts throughout the several views, 1 indicates the motor which 70 is mounted in the bifurcated depending arm 2 of the head 3 carried on the upper end of the sliding post 4 and which latter is mounted for sliding movement in the hollow post 5 mounted on the base 6, this is 75 the usual construction in the conventional form of drink mixers for mixing a single drink and the construction also includes an auxiliary head 7 mounted on the head 3 by a neck portion 8 or the like and carrying 80 oppositely directed spring arms 9 by means of which the post 4 may be readily raised when the device is not in use. The motor 1, of which the casing and the motor shaft 10, only are shown, may receive its electrical 90 energy by means of the conduction wires 11 projecting from the head 3 and extending into the casing of the motor 1 in the usual manner. This motor is also supported in proper upright position within the bifurcated arm 2 by a pair of bolts 12 on either side of the motor 1 and extended through these lower corners of the bifurcated arm 2 and through the motor casing. By referring to Figures 2 of the drawings, it will 95 be seen that the motor shaft 10 carries a bevel gear 13 and also has a carrying stem 14 depending therefrom with a conventional form of mixer 15 mounted on the lower end of the stem 14. The stem 14 may also be 100 termed a mixer carrying shaft.

In order to convert the single mixing machine above described into a multiple drink mixer, an attachment is provided therefor and which includes a pair of bearing brack- 110

ets 16 adapted to be placed on opposite sides of the motor 1 and outwardly of the bifurcated arm 2. Each bearing bracket 16 is provided with a pair of diverging perforated ears 17 at its upper end by means of which the bearing bracket 16 may be mounted on the bolts 12 on that side of the motor. Each bearing bracket 16 is preferably in the form of a casting and has its lower end flattened on opposite sides and extended toward and away from the motor shaft 10, as shown at 18 in Figure 2. From the lower portion 18 of the bracket 16 depend a plurality of bearing ears 19 through which may be extended a horizontal shaft 20 having a bevel gear 21 on one end to mesh with the bevel gear 13 while a second bevel gear 22 is carried on the opposite or outer end of the shaft 20. A bearing finger 23 is formed in the outer lower corner of each bracket 16 and the end brought around and turned back to form a vertical bearing 24 within the bearing finger 23. An auxiliary mixer carrying shaft 25 is rotatably mounted in the vertical bearing 24 and has a bevel gear 26 mounted on its upper end within the bearing finger 23 and meshing with the bevel gear 22 to be driven by the latter. A mixer 27 of conventional form is carried on the lower end of the auxiliary mixer carrying shaft 25. The mixers 27 are preferably in substantial alignment with the mixer 15, as shown in Figure 2 of the drawings.

From the foregoing paragraphs taken in connection with the accompanying drawings it will be evident that the auxiliary mixers 27 will be automatically operated with the mixer 15 so that the several mixers may serve to mix drinks in separate containers with the single operation of the mixing device. The attachment may be readily applied even by parties unskilled in the art of the manufacture and assembling such device and without special implements or machinery, as it is simply necessary to remove the bolts 12 and mount the brackets 16 thereon and then again secure the bolts 12 through the bifurcated arm 2 and the casting of the motor 1. In fact, should the device be originally assembled as a single mixer with nuts on the outer ends of the bolts 12, removal of the nuts will be the only operation necessary previous to the mounting of the brackets 16.

It is believed that the complete construction and operation as well as the advantages of the present invention will be understood by persons without further detailed description thereof. It is to be understood, that while the preferred embodiment of the invention has been shown and described minor details of construction and arrangement of parts may be resorted to within the scope of what is claimed without departing from the spirit of the invention.

Having thus described our invention, what we claim is:

1. In a device of the character described, the combination with a supporting post, of a sliding post held in said supporting post, having a bifurcated recurred depending arm, a motor fixed to said arm, a driving shaft, a pair of bearing brackets held to opposite sides of said recurred arm each bracket including a pair of bearing ears, a recurred bearing finger extending from each of said brackets having vertically aligned bearings, a horizontal shaft held in said bearing ears, a bevel pinion held to the inner end of each of said horizontal shafts, a driving pinion on said motor shaft in mesh with said pinions, a pinion on the outer end of each horizontal shaft, an auxiliary mixing shaft in the bearings of said recurred fingers, a mixing stem held to said driving shaft, a pinion on each of said last mentioned mixing shafts for meshing with the outer pinions on said horizontal shafts, whereby on rotating said main driving pinion, said auxiliary mixing stems are rotated.

2. The combination with a motor supported with its axis in a vertical plane and carrying a vertically disposed stirrer, of a bracket detachably secured to the motor and having a recurred depending part, bearings formed with the bracket and disposed in alignment with the recurred part, a horizontal shaft journaled in the bearings, driving connections between the horizontal shaft and the stirrer, a second stirrer journaled in the lower end of the recurred part of the bracket and driving connections between the horizontal shaft and the last mentioned stirrer.

In testimony whereof, we affix our signatures.

BARNEY GOLDSTEIN.
GEORGE L. McDONAUGH.
